CLAIM

The ornamental design for a cigar cutter, as shown and described.

DESCRIPTION

FIG. 1 is a front view of a cigar cutter in accordance with my invention, the rear view thereof being a mirror image; the broken lines are shown for illustrative purposes only and form no part of the claimed design;

FIG. 2 is a top view thereof;

FIG. 3 is a bottom view thereof; and,

FIG. 4 is a left side view thereof, the right side thereof being a mirror image.
